HEAVY DUTY FLOODLIGHT

Tarek B. Adra, La Canada, Calif., assignor to Harvey
Hubbel Incorporated, Bridgeport, Conn.

Filed Nov. 5, 1970, Ser. No. 25,844

Term of patent 14 years

Int. Cl. D26—04

U.S. Cl. D48—20

Fig. 1

Fig. 2.

Fig. 3

Fig. 4

Fig. 7.

FIG. 1 is a perspective view of a heavy duty floodlight showing my new design;

FIG. 2 is a front elevational view thereof;

FIG. 3 is a top plan view thereof;

FIG. 4 is a bottom plan view thereof;

FIG. 5 is a side elevational view thereof;

FIG. 6 is a rear elevational view thereof; and

FIG. 7 is a cross-sectional view taken on line 7-7 of FIG. 5.

The electric cord is broken away in FIGS. 2, 5 and 6 to indicate indeterminate length.

I claim:

The ornamental design for a heavy duty floodlight, substantially as shown and described.
